UNITED STATES PATENT OFFICE.

FREDERICK OUTRAM, OF MONTREAL, QUEBEC, CANADA.

SLIDING BED FOR MACHINERY.

SPECIFICATION forming part of Letters Patent No. 293,591, dated February 12, 1884.

Application filed December 4, 1882. Renewed November 6, 1883. (No model.) Patented in Canada July 5, 1882, No. 15,048.

To all whom it may concern:

Be it known that I, FREDERICK OUTRAM, of the city of Montreal, in the District of Montreal, and Province of Quebec, Canada, have 5 invented certain new and useful Improvements in Sliding Beds for Machinery; and I do hereby declare that the following is a full, clear, and exact description of the same.

This invention relates to improvements in 10 that class of beds which are used for carrying the blank in file-cutting machines, and for planers, drills, lathes, and like machinery, where it is necessary for one part of the bed to slide on another part of the same, for the 15 purpose of carrying the article being operated upon to and from the tool, &c., which acts upon such article.

The improvements consist, first, in the formation of grooves or channels in either the 20 sliding or stationary part of the bed, or both, longitudinally with the line of movement, in order to admit of the passage of air and oil—either or both—between the meeting surfaces of such sliding and stationary parts, for the 25 purpose of assisting in the easy movement of the sliding piece.

My invention consists, secondly, in the combination, with a semicircular bed—such as is sometimes used in file-cutting machines—of 30 feathers or tongues projecting from one section of the bed into similarly-formed ways in the other part of same, for the purpose of steady- 35 ing the sliding portion and keeping the same upright in its bed while the operation is per- formed upon the article carried on its upper surfaces.

The third part of the invention is the combination, with a semicircular bed piece or carrier, having one or more feathers or pro- 40 jections on its under side which fit into and slide in similarly-shaped ways in the station- 45 ary bed-plate, of air channels or grooves ar- ranged between the feathers at the junction of the two parts of the bed, cut in either or both, and extending longitudinally with said feathers.

To thoroughly comprehend my invention, reference must be had to the accompanying drawings, and to the following detailed de-

scription, in both of which similar letters of 50 reference indicate like parts.

In the drawings, Figure 1 represents my 55 ventilated bed applied to a common style of file-cutting machines. Fig. 2 is an enlarged view, showing semicircular bed provided with feathers and air-grooves. Fig. 3 is a perspective view partly broken away. Fig. 4 is a longitudinal sectional elevation of same, and Fig. 5 shows modified forms of ventilated bed.

A represents the stationary bed of the ma- 60 chine to which my invention may be applied, having its upper side channeled to receive the sliding carrier or bed-piece B, which is moved back and forth in said channel by whatever means may be suited to the purpose for which 65 the machine is used.

a a indicate any desired number of channels 70 or grooves cut in either the moving carrier B, on its under side, or in the face of the channel in the bed A, or in both, as shown, said grooves 75 a a running longitudinally with the bed, and serving to admit air at the meeting surfaces in such manner as will prevent the formation of a vacuum from the constant pressure downward of the sliding piece, these grooves also 80 lessening the frictional surface, and also serving in some measure as reservoirs for the oil used in lubrication, and for the grit, dust, and scale, &c., which would otherwise interfere with the free working of the bed.

b b represent the feathers or projections 85 from the under side of the sliding carrier B, fitting into the similarly-formed ways in the bed A, (three being used by preference,) the arrangement of which, as will be readily seen, 90 absolutely prevents the sliding carrier from turning in its semicircular bed, and therefore overcomes the objections heretofore found in half-round beds of this class, where no means of steadyng same were employed.

It will be apparent that by the use of either 95 or the elements of my invention—i. e., the air-channels and the feathers—or a combination of both, a sliding bed can be made to work very easily, the friction being greatly lessened, and simple and efficient means being provided to keep the bed steady and upright.

Having thus described my invention, what I

claim, and desire to secure by Letters Patent, is as follows:

1. In a file-cutting or like machine, a stationary bed and a carrier sliding therein having at their meeting surfaces longitudinal grooves.

2. The combination, in a file-cutting or like machine, of a bed-plate having a number of longitudinal grooves, and a traveling carrier

having a number of corresponding longitudinal feathers formed integral with it, and adapted to engage with the grooves in the said bed-plate, substantially as and for the purpose set forth.

F. OUTRAM.
